UNITED STATES PATENT OFFICE

132,350

DESIGN FOR A BAR OF SOAP

Harold B. Stoner, Dayton, Ohio, and Richard W. Angert, Camp Hulen, Tex., assignors to The Hewitt Soap Company, Inc., Dayton, Ohio, a corporation of Ohio

Application November 26, 1941, Serial No. 104,347

Term of patent 14 years

To all whom it may concern:

Be it known that we, Harold B. Stoner and Richard W. Angert, citizens of the United States, and residents of Dayton, in the county of Montgomery and State of Ohio, and Camp Hulen, in the county of Matagorda and State of Texas, respectively, have invented a new, original, and ornamental Design for a Bar of Soap, of which the following is a specification, reference being had to the accompanying drawing, forming a part thereof.

In the drawing:

Figure 1 is a front elevational view of the bar of soap, showing our new design.

Figure 2 is a top plan view of the same.

Figure 3 is an end elevational view of the same.

We claim:

The ornamental design for a bar of soap, substantially as shown.

HAROLD B. STONER.
RICHARD W. ANGERT.
